UNITED STATES PATENT OFFICE.

EDWARD GERMAIN, OF SAGINAW, MICHIGAN.

DESIGN FOR A MANTEL.

SPECIFICATION forming part of Design No. 21,159, dated November 10, 1891.

Application filed October 14, 1891. Serial No. 408,727. Term of patent 7 years.

To all whom it may concern:

Be it known that I, EDWARD GERMAIN, of Saginaw, in the State of Michigan, have invented a new and original Design for Mantels, 5 of which the following is a specification, reference being had to the accompanying drawings, in which—

Figure 1 is a front elevation of the mantel. Fig. 2 is a transverse vertical sectional elevation of the same.

In the drawings, *a* are the pilasters. *b* are the plinths; *c*, the caps; *d*, the mantel-board; *e*, the frieze; *f*, the grounds, and *g* the fire-strips.

15 The pilasters *a* have side edges beveled and molded, as shown at *a'*. The face of each pilaster is divided into raised panels *a²*, *a³*, and *a⁴*. In each of the narrow panels *a²* *a³* are two pits or indented dots *h*. In the larger 20 intermediate panels *b⁴* are two parallel intagliated diagonal lines *i* in the space, between which are two pits or indented dots *h'*. The upper portion of the front of each plinth is molded, as shown at *j* in Fig. 1 and in side 25 outline in Fig. 2.

Each cap *c* has its lower edge and the portions of its side edges immediately adjacent

thereto beveled and molded, as seen at *k*, and upon its face is a rosette *l* in relief. Immediately beneath the mantel-board and upon 30 each cap is a pair of quarter-round brackets *m*, having molded outer edges.

The lower edge of the frieze is molded, as at *n*, and beneath it is a quarter-molding *n'*. Upon the frieze is raised a panel *o*, of rectangular outline, having molded edge, and carrying also two pairs of diagonal indented lines *p*, inclined in opposite directions, with indented dots or pits *p'* in the space included between the two lines of each pair. 35

Beneath the mantel-board is a molding *r*.

The edges of the mantel-board, the fire-strips *g*, and the outside side strips of the grounds *f* are molded, as shown.

What I claim, and desire to secure by Letters Patent, is—

The design for a mantel, as herein described and shown.

In testimony whereof I affix my signature in presence of two witnesses.

EDWARD GERMAIN.
